U.S. Appl. No. 29/450,193, filed Mar. 15, 2013, Royer.

* cited by examiner

Primary Examiner — Susan Bennett Hattan*Assistant Examiner* — Vy Koenig(74) *Attorney, Agent, or Firm* — Oblon, Spivak, McClelland, Maier & Neustadt, L.L.P.(57) **CLAIM**

The ornamental design for a package for cup, as shown and described.

DESCRIPTION

FIG. 1 is a top unfolded view of a package for cup;
FIG. 2 is a front unfolded view thereof;
FIG. 3 is a rear unfolded view thereof;
FIG. 4 is a left side unfolded view thereof, where the right side unfolded view is the mirror image of the left side unfolded view thereof;
FIG. 5 is a front folded view thereof;
FIG. 6 is a rear folded view thereof;
FIG. 7 is a left folded view thereof;
FIG. 8 is a right folded view thereof; and,
FIG. 9 is a bottom, left, and perspective view thereof.
The broken lines in the drawings depict environmental subject matter only and form no part of the claimed design.
